(57) **CLAIM**

The ornamental design for a penile erectile aid, as shown and described.

DESCRIPTION

FIG. 1 is a side perspective drawing of a penile erectile aid showing my new design, viewing the device from the front and right side;

FIG. 2 is a rear elevation view thereof;

FIG. 3 is front elevation view thereof;

FIG. 4 is a top plan view thereof;

FIG. 5 is a right side elevation view thereof;

FIG. 6 is a left side elevation view thereof; and,

FIG. 7 is a bottom elevation view thereof.

In FIG. 1, a penis is shown in broken lines for illustration purposes only and form(s) no part of the claimed design.
